(57) **CLAIM**

The ornamental design for a ring-shaped golf alignment stick stand, as shown and described.

DESCRIPTION

FIG. 1 is perspective view showing our ring-shaped golf alignment stick stand design;

FIG. 2 is a top plan view of our ring-shaped golf alignment stick stand design;

FIG. 3 is a front elevation of our ring-shaped golf alignment stick stand design shown in FIG. 2;

FIG. 4 is a side elevation thereof rotated clockwise 90° from the view of FIG. 3;

FIG. 5 is a back elevation thereof rotated clockwise 180° from the view of FIG. 3;

FIG. 6 is an opposite side elevation thereof rotated clockwise 270° from the view of FIG. 3; and,

FIG. 7 is a bottom plan view of our ring-shaped golf alignment stick stand design.

The broken lines on the drawings form no part of the claimed design.

1 Claim, 5 Drawing Sheets
